Primary Examiner — Austin Murphy(74) *Attorney, Agent, or Firm* — Terrile, Cannatti, Chambers & Holland, LLP; Robert W. Holland(57) **CLAIM**

We claim the ornamental design for an information handling system storage device carrier, as shown and described.

DESCRIPTION

FIG. 1 is a front perspective view of the information handling system storage device carrier comprising the present invention;

FIG. 2 is a front view thereof;

FIG. 3 is a left side view thereof;

FIG. 4 is a right side view thereof;

FIG. 5 is a top view thereof; and,

FIG. 6 is a bottom view thereof.

Broken lines shown in the drawings illustrate portions of the information handling system storage device carrier, and form no part of the claimed design.
